UNITED STATES PATENT OFFICE.

HENRY N. SNYDER AND LEWIS A. HARDISON, OF SANTA PAULA,
CALIFORNIA.

ELECTRIC FUSE.

No. 799,684.

Specification of Letters Patent.

Patented Sept. 19, 1905.

Application filed August 8, 1904. Serial No. 219,926.

To all whom it may concern:

Be it known that we, HENRY N. SNYDER and LEWIS A. HARDISON, citizens of the United States, residing at Santa Paula, in the county 5 of Ventura and State of California, have invented certain new and useful Improvements in Electric Fuses; and we do declare the following to be a full, clear, and exact description of the invention, such as will enable others 10 skilled in the art to which it appertains to make and use the same.

Our invention relates to improvements in mounts or holders for fusible conductors of electric cut-outs, and particularly to that class 15 of such devices in which the fuse is entirely inclosed and so mounted that it may be readily renewed when destroyed or damaged.

The object of our invention is to provide a device of this character which will be simple 20 in construction, durable in use, efficient in operation, and comparatively inexpensive to manufacture.

With the above and other objects in view the invention consists of certain novel features 25 of construction, combination, and arrangement of parts, as will be hereinafter more fully described, and particularly pointed out in the appended claim.

In the accompanying drawings, Figure 1 is 30 a front elevation of our improved electric fuse. Fig. 2 is a longitudinal sectional view taken on the line 2 2 of Fig. 1. Fig. 3 is a transverse sectional view taken on the line 3 3 of Fig. 1, and Fig. 4 is a detail view of the fuse- 35 support and its electric conductor-terminals.

Referring to the drawings by numeral, 1 denotes a tubular body constructed of glass or other non-conducting material and having its ends closed by caps 2 and 3. Said closures 40 or caps 2 may be of any suitable material and constructed in any desired manner, so that the body 1 may be adapted to contain oil or other liquid. As shown in the drawings, we have formed upon the ends of the body 1 screw-threads 4, which are engaged by screw-threads 5, stamped or otherwise formed in the caps 2 and 3. A packing in the form of a washer of rubber or other suitable material is interposed between the ends of the tubular 50 body and the caps in order to effect a liquid-tight joint or connection.

Disposed longitudinally within the bore of the body 1 is a fuse-support 7, constructed of suitable non-conducting material and having

secured at each of its ends a block 8, of porcelain or other non-conducting material. Riveted or otherwise secured, as at 9, to each of the blocks 8 is an electric conductor-terminal 10, which comprises a body portion 11 and a screw-threaded stem 12, which projects through a central opening formed in one of the caps or closures upon the ends of the body 1. Upon these outer screw-threaded ends 12 are packing-washers 13 and clamping-nuts 14, which hold the fuse-support 7 and its conductor-terminal 10 centrally within the body of the device. The fuse-support 7 is preferably of zigzag shape, as clearly shown in Fig. 1, and is formed with a longitudinally-disposed bore or passage 15, through which a fusible 70 conductor 16 is adapted to pass. The ends of the fuse 16 are secured by washers 17 and screws 18 to the body portion 11 of the electric conductor-terminal 10. The space within the body 1 around the fuse-support 7 and the 75 fuse 16 is adapted to be filled with a suitable oil or other liquid, (indicated at 19 in Fig. 2.)

The operation and advantages of our electric fuse will be readily understood from the foregoing description, taken in connection 80 with the accompanying drawings, and it will be seen that when the fuse 16 is blown the parts may be readily separated and a new fuse placed in the support 7. By constructing said support 7 as shown and passing the fuse 85 through the holes in the angular portions of the same said angular portions will interrupt the arc formed when the current is short-circuited.

While we have shown and described the preferred embodiment of our invention, it will be seen that we do not wish to be limited to the precise construction herein set forth, since various changes in the form, proportion, and the minor details of construction may be resorted to without departing from the principle or sacrificing any of the advantages of this invention.

Having thus described our invention, what we claim as new, and desire to secure by Letters Patent, is—

An electric fuse comprising a tubular body having screw-threaded ends, screw-caps for closing said ends, a zigzag fuse-support of non-conducting material within said body, said support having a longitudinal bore therethrough, electrical conductor - terminals secured upon the ends of said support and hav-

ing screw-threaded ends projecting through said screw-caps, clamping-nuts upon the outer ends of said terminals, a fusible conductor passing through said longitudinal bore and connecting the inner ends of said terminals, and a liquid in said body surrounding said fusible conductor and said support, substantially as described.

In testimony whereof we have hereunto set our hands in presence of two subscribing witnesses.

HENRY N. SNYDER.
LEWIS A. HARDISON.
